UNITED STATES PATENT OFFICE.

ALBEN E. LUNDELL, OF NEW YORK, N. Y., ASSIGNOR, BY MESNE ASSIGNMENTS, TO
WESTERN ELECTRIC COMPANY, INCORPORATED, A CORPORATION OF NEW YORK.

TELEPHONE-EXCHANGE SYSTEM.

1,245,478.

Specification of Letters Patent.

Patented Nov. 6, 1917.

Application filed October 23, 1915. Serial No. 57,449.

To all whom it may concern:

Be it known that I, ALBEN E. LUNDELL, a citizen of the United States, residing at New York, in the county of Bronx and State of New York, have invented certain new and useful Improvements in Telephone-Exchange Systems, of which the following is a full, clear, concise, and exact description.

This invention relates to telephone exchange systems, and particularly to telephone exchange systems of the semi-automatic type.

In the installation of semi-automatic telephone systems it has been the practice to install district and office machines having groups of fifty trunks each. This practice usually results in having an equipment which at the time of installation is much larger than is required to handle the traffic, with the result that a large portion of the equipment remains idle until the increase in traffic necessitates its being brought into use. It is desirable to employ different groups of different sizes at the time of installation, and these groups ought to be capable of increase or decrease, depending upon variations in traffic at some future time. It is also desirable to be able to use any office key for calling any office so that the office buttons can be kept arranged in alphabetical order regardless of additional installations.

The object of this invention is, therefore, to provide means for readily altering the control of the district and office registers.

The accompanying drawing illustrates the invention applied to a semi-automatic telephone system, only so much of the system being shown as is necessary for an understanding of the invention. For a detailed description of a telephone system to which this invention is applicable, reference may be had to Patent No. 1,125,579 of January 19, 1915, granted to F. R. McBerty, or to Patent 45 1,168,319 of January 18, 1916, granted to A. E. Lundell.

In the drawings a plurality of keys are provided, of which but three keys, 10, 11 and 12, are shown. These keys are connected one side to the terminals of one section of a cross-connecting rack 13, the other side to the terminals of another section of this connecting rack. A group of nine relays, of which but two, 14 and 15, are shown, are

connected one side to the terminals of the first section of the cross-connecting rack 13 and the other side to a rack 16. To this rack 16 is also connected a start relay 17.

To the second section of the cross-connecting rack 13 is connected a second group of five relays, of which but two, 18 and 19, are shown. The relation between the start relay 17, the group of relays of which 14 and 15 are representative, and the group of relays of which 18 and 19 are representative, is such that the start relay 17 and one from each group of the two groups of relays are always energized in series. Also with the nine relays in one group and the five relays in the other, it is possible to obtain forty-five different combinations of two offices each, the forty-five different combinations being obtainable by forty-five different keys having two contacts each instead of having to use four contacts on each key, as would be the case ordinarily. The manner of selecting a brush and group by means of a key will now be described in detail, as it is thought that in this manner the invention will be most clearly understood.

An operator, having received instructions from a subscriber to connect him with another subscriber in the system, for instance, one located in the main exchange, depresses a key representing this exchange, and it is assumed that this key is the one numbered 10 on the drawing. The depression of this key closes a circuit from battery, start relay 17, the rack 16, group relay 14, the contact in the cross-connecting rack 13, the depressed key 10, the contact in the cross-connecting rack 13, group relay 18 to ground, energizing the start relay 17 and the group relays 14 and 18 in series. The group relay 14 energizing, attracts its armature and places a ground at its armature and front contact on the point numbered 6 of the group register 20. The energization of the group relay 18 places a ground on the point numbered 2 of the brush register 21. The energization of the start relay 17 completes energizing circuits for the motor magnets of the group and brush registers 20 and 21 over the following paths: battery, motor magnet of group register 20, conductor 22, inner armature and back contact of cutoff relay 23, conductor 24, armature and front contact of start relay 17 to ground; and from battery,

motor magnet of brush register 21, conductor 25, armature and back contact of cutoff relay 26, conductor 24, armature and front contact of start relay 17 to ground. The group 5 register 20 revolves until it reaches its sixth position, in which position a circuit is closed from battery, cutoff relay 23, conductor 27, contact spring 28, conductor 29, armature and front contact of group relay 14 to ground. The cutoff relay energizing breaks the circuit of the motor magnet of the group register, stopping the same in the sixth position. The brush register revolves until it reaches its second position, at which time a 15 circuit is closed from battery, cutoff relay 26, contact spring 30, conductor 31, armature and front contact of group relay 18 to ground. The closure of this circuit energizes the cutoff relay 26, breaking the energizing circuit for the motor magnet of the brush register, stopping the register in its second position.

The cutoff relays 23 and 26 being now energized, a circuit is closed from battery, 25 motor magnet of sender sequence switch 32, conductor 33, lower right contact of sequence switch spring 34, conductor 35, outer armature and front contact of cutoff relay 23, conductor 36, armature and front contact 30 of cutoff relay 26, conductor 24, armature and front contact of start relay 17 to ground, energizing the motor magnet of the sender sequence switch 32, and moving the same from position 1 into position 6. In 35 position 6 of the sender sequence switch 32 a circuit is closed from battery, line relay 37 of the selector, conductor 38, upper left contact of sequence switch spring 39, stepping relay 40, conductor 41, armature and back contact of the #0¹ counting relay, conductor 42 to ground. The line relay 37 energizes, attracting its armature and closing a circuit for the motor magnet of the selector sequence switch 43 from battery, 45 motor magnet, conductor 44, upper left contact of sequence switch spring 45, conductor 46, armature and front contact of line relay 37 to ground, moving the sequence switch from position 1 into position 2. In position 2 a circuit is closed from battery, the 50 brush selecting magnet 47, upper right contact of sequence switch spring 45, conductor 46, armature and front contact of line relay 37 to ground, energizing the brush selecting magnet and tripping the proper set of brushes. In position 6 of the sender sequence switch 32 a circuit is closed from battery, the #1 counting relay, armature and back contact of the #1¹ counting relay, 55 conductor 48, the upper right and lower left contacts of brush register sequence switch spring 49, conductor 50, upper right contact of sender sequence switch spring 51, armature and front contact of stepping relay 40 to ground. In position 2 of the selector 60

sequence switch 43 a circuit is closed from ground at the interrupter 52, upper right contact of sequence switch spring 53, conductor 60, to the junction of the conductor 60 with conductor 38, shunting the circuit through the stepping relay 40, deenergizing and energizing the stepping relay the necessary number of times for running down the counting relay circuit in the usual manner. Upon the energization of the #0¹ counting 70 relay the circuit through the stepping relay 40 is broken at its left armature and front contact, and a circuit for the motor magnet of the sender sequence switch 32 is closed at its right armature and front contact over the following circuit: battery, motor magnet, conductor 33, upper right contact of sequence switch spring 34, conductor 53, right armature and front contact of the #0¹ counting relay to ground to move sequence switch 32 from position 6 into position 8. In moving out of position 8, the sender sequence switch 32 breaks, at the lower and upper left contacts of sequence switch spring 59, the energizing circuit for the counting 80 relays, which thereupon return to normal. At the end of the last shunting impulse from interrupter 52, the energizing circuit for the line relay 37 of the selector was broken, the armature of which, retracting, completed a circuit from battery, motor magnet of selector sequence switch 43, conductor 54, upper right contact of sequence switch spring 55, conductor 56, armature and back contact of line relay 37 to ground, moving the sequence switch 43 from position 2 into position 3. The sender sequence switch 52 being now in position 8, the energizing circuit for the line relay 37 of the selector and the stepping relay 40 is again completed 90 over the path above traced.

The energization of the stepping relay 40 completes a circuit from battery through the appropriate counting relay to the upper right contact of group register sequence switch spring 66, conductor 57, lower right contact of sender sequence switch spring 51, armature and front contact of relay 40 to ground, preparatory to sending the impulses necessary for group selection.

The energization of the line relay 37 of the selector completed a circuit from battery, motor magnet of selector sequence switch 43, conductor 44, upper left contact of sequence switch spring 45, conductor 46, armature and front contact of line relay 37 of the selector to ground, moving the sequence switch 43 from position 3 into position 4, in which position a circuit is closed from battery, brush selecting magnet 58, lower right contact of sequence switch spring 45, conductor 46, armature and front contact of line relay 37 to ground to select the proper group. Also in position 4 of the sequence switch 43, a circuit is closed from 115

ground at the interrupter 52 to control the counting relay circuit in the manner above described for brush selection.

What is claimed is:

5 1. In a telephone system, the combination with groups of relays, a register under control of each group of said relays and keys for controlling said relays, of means for alternating the relation between said keys
10 and said relays.

2. In a telephone system, the combination of registers, a group of relays for controlling the setting of each of said registers, a plurality of keys for controlling said relays, and means for shifting the control of said 15 relays by said keys.

In witness whereof, I hereunto subscribe my name this 18th day of October, A. D. 1915.

ALBEN E. LUNDELL.
